UNITED STATES PATENT OFFICE.

ORIN C. DONECKER AND JACOB A. NAGLE, OF ALLENTOWN,
PENNSYLVANIA.

AUTOMATIC FIRE-DOOR.

SPECIFICATION forming part of Letters Patent No. 726,034, dated April 21, 1903.

Application filed September 5, 1902. Serial No. 122,258. (No model.)

To all whom it may concern:

Be it known that we, ORIN C. DONECKER and JACOB A. NAGLE, citizens of the United States, residing at Allentown, in the county 5 of Lehigh, State of Pennsylvania, have invented a new and useful Improvement in Automatic Fire-Doors, of which the following is a specification.

Our invention relates to a novel construction of apparatus for preventing flames from ascending in elevator-shafts, light-shafts, well-openings, and similar passages in the case of fire; and it consists in the novel combination of mechanism whereby doors made 15 of fireproof material are caused to be normally held in open position; but upon the occurrence of a fire the heat generated thereby will cause the locking devices for said doors to be released, whereby the doors will 20 automatically fall, and thereby check the upward sweep of flames through the shaft from one story to another. The doors are preferably hung on spring-hinges, which serve to assist in the descent of the said doors when 25 released.

The invention further consists of novel details of construction, all as will be hereinafter fully set forth.

Figure 1 represents a vertical sectional view of an automatic apparatus for elevator-shafts embodying our invention. Fig. 2 represents a section on line *x x*, Fig. 1. Fig. 3 represents a section on line *y y*, Fig. 1, but with the doors shown in closed position. Fig. 35 4 represents a section on line *z z*, Fig. 2.

Similar numerals of reference indicate corresponding parts in the figures.

Referring to the drawings, 1 designates the walls or casing of an elevator-shaft, light-shaft, well-opening, or the like embodying our invention.

2 designates doors, which are hinged at the points 3 to any suitable support, it being understood that said doors are normally in open 45 or upright position, as will be understood from Figs. 1, 2, and 4, said doors, however, being shown in closed or substantially horizontal position in Fig. 3, said doors being held in their horizontal position by means of the 50 abutments 4.

2^a designates ropes attached to the main

doors near their centers, as seen by dotted lines in Fig. 1 and full lines in Fig. 3. These ropes may extend to any desired point, where they may be used for raising the doors by 55 hand when desired.

5 designates a hook or staple attached to the upper side of the doors 2, which when said doors are in open position, as indicated in Figs. 1 and 2, is in alinement with a pair of 60 hooks or staples 6, which are secured in fixed position to a wall of the shaft 1.

7 designates a bolt, which may be a plain cylindrical piece of metal secured to the lower extremities of branches of the rope, chain, or 65 other connection 8, which latter passes over the pulleys 9 and is attached to the weight 10, said weight being held in position by means of the connection 11, which passes over the pulley 12 and thence downwardly 70 under the pulley 13 and thence over the pulley 14, as indicated at the lower right-hand portion of Fig. 2, it being understood that the lower portion of the connection 11 is secured to any suitable fixed point, being carried 75 down as many floors as desired.

15 designates a fusible link or chain inserted in the connection 11, substantially in the position indicated in Fig. 2, so that said connection normally is located between the pulleys 13 and 14, whereby in case of fire the fusible portion of the connection will melt, thereby permitting the weight 10 to fall. 80

The operation is as follows: The parts normally appear as seen in Figs. 1 and 2, the doors 2 being in open position, so that the passage of the elevator-car is not impeded. In case of fire the heat melting the fusible link 15 will cause the weight 10 to be unsupported and the same will fall, thereby exerting a pull upon the connections 8, and thus removing the locking bolts or pins 7 from their engagement with the eyes or staples 5 and 6, whereupon the doors 2 will fall and assume the position seen in Fig. 3. 90

We have not deemed it necessary to describe in detail the function of the cables or connections 16, since the same *per se* form no part of our invention, as the same is applicable to any form of elevator or shaft. 95

In practice we hinge to the main doors two auxiliary doors 17, which are secured in po- 100

sition by the hinges 18, said doors being folded back upon the main doors 2, as will be understood from Fig. 2, when said main doors are in elevated position, it being, however, 5 understood that said auxiliary doors are caused to be turned into the position seen in Fig. 3 when the main doors 2 fall by reason of the springs 19, the construction of which may be varied according to requirements.

10 It will of course be understood that suitable checking devices or buffers may be employed to prevent the main doors 2 from descending too abruptly when the locking pin or bolt 7 is released. It will further be apparent 15 that various changes may be made by those skilled in the art which will come within the scope of our invention, and we do not, therefore, desire to be limited in every instance to the exact construction shown and 20 described.

Having thus described our invention, what we claim as new, and desire to secure by Letters Patent, is—

1. In a device of the character named, the 25 combination of a shaft, a main door therein mounted to swing from a horizontal to a vertical position, an eye or staple on said main door, and an eye or staple secured to a wall of said shaft, said eyes being in proximity 30 when the door is opened, a locking-pin adapted to engage said eyes, said eyes and locking-pin being behind the door and parallel therewith when the latter is in its open position, a connection extending from said pin around 35 a pulley and having a weight thereon, a connection from said weight passing around another series of pulleys, and a fusible link in said connection whereby the heat generated in case of fire will melt the same and cause 40 said main door to automatically fall.

2. In a device of the character named, the 45 combination of a shaft, a main door therein mounted to swing from a horizontal to a ver-

tical position, an eye or staple on said main door, and an eye or staple secured to a wall 45 of said shaft, said eyes being in proximity when the door is opened, a locking-pin adapted to engage said eyes, said eyes and locking-pin being behind the door and parallel therewith when the latter is in its open position, a 50 connection extending from said pin around a pulley and having a weight thereon, a connection from said weight passing around another series of pulleys, a fusible link in said connection whereby the heat generated in 55 case of fire will melt the same and cause said main door to automatically fall, an auxiliary door hinged to said main door and adapted to be normally folded back upon said main door, and a spring for closing said auxiliary door 60 when the main door drops.

3. In a device of the character named, the combination of a shaft, main doors hinged therein, auxiliary doors 17 hinged to said main doors and adapted to be folded back 65 upon said main doors when the latter are in open position, a spring common to said doors for closing said auxiliary doors when the main doors fall, locking devices 5 and 6 common to said main doors, and a wall of said shaft, 70 locking-pins adapted to engage said devices, connections from said pins, pulleys over which said connections pass, a weight to which an end of said connections is secured, another connection extending from said 75 weight, pulleys around which said last-mentioned connection passes, and a fusible link in said last-mentioned connection.

In testimony whereof we have signed our names to this specification in the presence of 80 two subscribing witnesses.

ORIN C. DONECKER.

JACOB A. NAGLE.
